COMBINATION FINGER AND TOE NAIL CLIPPER

Anthony N. D'Elia, 3555 Netherland Ave., Riverdale, N.Y. 10471, and Edward M. Stolarz, 30 W. 60th St., New York, N.Y. 10023

Filed Oct. 17, 1966, Ser. No. 4,300

Term of patent 14 years

(Cl. D86—10)

FIG. 1

FIG. 2

FIG. 6

FIG. 3

FIG. 4

FIG. 5

FIG. 1 is a perspective view of a combination finger and toe nail clipper embodying our new design, shown with one actuating lever in a raised position;

FIG. 2 is a side elevational view thereof, shown with both actuating levers in a closed position;

FIG. 3 is a side elevational view, shown with the other actuating lever in a raised position, the view from the opposite side being identical;

FIG. 4 is a top plan view thereof;

FIG. 5 is a bottom plan view thereof; and

FIG. 6 is a perspective view thereof, shown with both levers in a closed position.

We claim:

The ornamental design for a combination finger and toe nail clipper, as shown and described.
